UNITED STATES PATENT OFFICE

HENRY JANSEN, OF CHICAGO, ILLINOIS

CUTTING TOOL

Application filed October 20, 1928. Serial No. 313,667.

My invention relates in general to cutting tools and more in particular to a type of cutting tool known in the trade as a groove bit.

Up until a comparatively short time ago all power driven wood working tools were of stationary nature, generally so that the cutting tool is mounted in operable position with respect to a table and the wood to be shaped is carried to the table where it is operated upon. Recently, particularly for doing certain kinds of work, portable power tools have been developed. An example of this is a slotting tool which is used extensively for cutting slots in window frames after the frames are hung in the building. Considerable difficulty has been had in obtaining a fully satisfactory operation of these tools. They are equipped with small light cutters generally called groove bits and must be run at quite high a speed in order for the workmen to use them satisfactorily. There is a limit, however, to the speed at which these tools may be run because the cutter burns very easily if the speed is too great.

It has been suggested in connection with these tools that a four bladed cutter be used instead of the present standard two bladed cutter. But this has been found to be impractical for a great many reasons which will be apparent from the following disclosure.

Accordingly the principal object of my invention is the provision of an improved rotary cutting tool.

Another object is the provision of a groove bit having more than the usual number of cutting blades.

Another object is the provision of an improved groove cutter.

Other objects and features of the invention will be apparent from a consideration of the detailed description taken with the accompanying drawings, wherein

Fig. 1 is an elevational view partly in longitudinal section showing a portion of a port-

able groove cutter, and illustrating the manner in which the tool is used;

Fig. 2 is a front view thereof, and

Figs. 3 and 4 are enlarged perspective views of the two portions of the cutter.

Whereas the main feature of my invention may be applied to cutters having a somewhat different form than that shown I have in actual practice applied my invention to the general type of groove cutter shown in the drawings and it is to this use that I find the invention particularly adapted.

In a portable cutter of this character (which incidentally I show somewhat schematically) a motor 10 is provided having a shaft 11 and an end framework 12 to which a suitable guard casting 13 is secured. This guide comprises a flat plane portion 14 with a middle housing 16 forming a guard for the cutting tool. An apron guide 17 is also provided for regulating the position of the cutter with respect to the work 18 as indicated in Fig. 1. In the tool as actually constructed I provide adjusting means so that the various positions of the guide casting may be regulated, so that both the depth and side-wise positions of the groove may be controlled. I have not shown the details of this arrangement in the present case, however, because the invention does not concern itself primarily therewith.

As to the cutting tool itself which in the Figs. 1 and 2 I designate generally by the reference character A, this tool is secured on the shaft 11 by means of nuts 19—19 and spacers 21—21 are utilized to regulate the position of the cutter along the shaft 11.

Substantially all of the structure described in the preceding paragraphs is old in the art, my invention having to do primarily with the cutter per se. The cutter as I now use it comprises two parts 22 and 23 as shown in Figs. 3 and 4 respectively. These two parts are complementary to each other so that when they are fitted together the knives will cut in

exactly the same line. The two cutters are identical with the exception that one is a left hand cutter and the other a right hand cutter, that is to say they are a pair and when put together, one opposing the other, both cut in the same direction. I shall describe the cutter 22 in detail it being understood that the cutter 23 is similar in all respects.

The cutter 22 is provided with a central aperture 22^a for receiving the motor shaft and its midportion 22^b from which the hub is provided with a square recess half the depth of the material of the tool at this point. There are two projecting knives 22^c and 22^d 10 both designed in the same manner so that a very sharp cutting edge is provided. The two portions of the cutter are fitted together by being placed at right angles to each other and having the recess coinciding so that the portion 22^b lies up against the portion 23^b 15 and a hub portion is formed of the same thickness as if no recess were formed. The two portions of the cutter are located together obtaining the same structural effect 20 as if a single unitary structure existed.

When the cutters have been formed to the proper shape and preliminary to finishing the knives with the usual shape cutting edge the ends or cutting edges of the tools are hardened, the inside or hub portion being left unhardened to maintain the requisite tensile strength. In this way toughness is retained and still the edges of the knives are sufficiently hard to retain a keen cutting edge. 30 This is one of the principal advantages obtained by my improved tool because with a four bladed knife manufactured from a single piece of tool steel it is impossible or at least impracticable to harden the ends or cutting edges, and so breakages are so frequent 35 that this type of tool is not used for small cutters.

The invention is applicable to other tools besides the type shown in the drawings but it is this tool with which I have had such good results. This tool is of general rectangular shape with an axial shaft receiving opening with the leading edge cut away and the outside end formed arc shape to produce a sharp 45 cutting edge. It is not meant necessarily to restrict the invention to use with this particular type of tool, but the invention is limited only by the scope of the appended claim.

What I claim as new and desire to protect by Letters Patent of the United States is:

A rotary, grooving, cutter having four blades, which permits of less rapid rotation for same penetration in cutting, than a lesser 50 number and yet leaves sufficient space between successive blades for ample chip clearance, said cutter consisting of two members identical except as to a right and left or counterpart relation for mutual interfitting 55 engagement, comprising a medial square re-

cess or transverse groove whose depth is half the thickness of each member, and whose width is that of the member and so mutually interfitted as to form a rigid cutter with four blades all of which are bounded by the 60 same radial planes, each member having on diagonally opposite or leading sides a semi-circular recess extending from a peripheral cutting edge to the line of intersection of the members.

In witness whereof I hereunto subscribe my name this 8th day of October, 1928.

HENRY JANSEN.
